PARTITION STRUCTURE

Bruno E. Balduf, Chicago, Ill., assignor to United States Gypsum Company, Chicago, Ill., a corporation of Illinois

Application December 15, 1937, Serial No. 179,967

2 Claims. (Cl. 72—46)

This invention relates to building constructions, and has reference more particularly to partition structures of the type commonly known as solid lath and plaster partitions.

Various constructions have been proposed for solid lath and plaster partitions which are commonly non-load bearing and are usually about 2" thick. These proposed constructions have often been lacking in the requirements of low cost of materials and ease of erection.

An object of this invention therefore is to provide a solid lath and plaster partition structure which will have a low material cost and will be easy to erect; also to improve building constructions in other respects hereinafter specified and claimed.

Reference is to be had to the accompanying drawings forming a part of this specification, in which

Fig. 1 is a perspective rear view of the improved partition,

Fig. 2 is a fragmentary elevation of the face of the partition,

Fig. 3 is a perspective rear view on a large scale of the bottom of the partition,

Fig. 4 is a transverse sectional view through the portion taken on line 4—4 of Fig. 2,

Fig. 5 is a perspective view of a modified form of partition structure,

Fig. 6 is a sectional perspective elevation on a large scale of a portion of the partition shown in Fig. 5,

Fig. 7 is a transverse section view through the partition taken on line 7—7 of Fig. 8,

Fig. 8 is a fragmentary elevation of a portion of the partition shown in Fig. 5, and

Fig. 9 is a perspective view of a modified form of board attaching clip for the partitions.

Referring to the drawings by numerals, a base channel 10 has a web 11 secured to a floor by nails 12 or other suitable fastening means, and has upstanding flanges 13 and 14. The flange 13 is provided with slots 15 at spaced intervals which are adapted to snugly receive the web 16 of a vertical stud channel 17, the latter having outstanding flanges 18 and 19. The flange 19 extends within the flange 13 so that the greatest part of the width of stud 17 extends beyond the flange 13. An upper channel similar to channel 10 may be secured to the ceiling to engage the upper ends of stud channels 17.

Plaster boards 21 of any suitable material for forming a base for plaster, engage at their bottom edges in base channel 10 between the flanges 14 and 19. These boards 21 may be gypsum

boards having a gypsum core 22 and paper cover sheets 23, said boards being preferably provided with spaced holes 24 to permit proper keying of plaster 25 which is applied to both sides of the partition to produce a partition about 2" thick faced on both sides with smooth plaster. Between their abutting edges, the boards 21 are secured to the stud channels 17 by means of wires 26 which are twisted about the stud 17 and embrace the web 27 of a board attaching clip having outstanding fingers 28 adapted to engage abutting edges of the boards. The base and ceiling channels 10 may conveniently have a width of web of $\frac{1}{2}$ " to $\frac{3}{8}$ " while the stud channels 17 may have a web width of $\frac{3}{4}$ ".

The modified partition shown in Figs. 5-8 differs from that shown in Figs. 1-4 in that vertical stud channels 30 have their webs 31 extending parallel to the plane of the partition. A pair of slots 32 is formed in one flange 33 of a base channel 34 and a similar ceiling channel not shown. Flanges 35 of stud channels 30 engage in the slots 32 so as to maintain said channels in upright position with the webs 31 lying in face abutting position against the plaster boards 21. In erecting this form of partition, plaster layer 37 is first applied to the surface of the boards 21 opposite the channels 30 so that keys or lugs of plaster 38 are forced through the openings 24. When this layer of plaster 37 has set, a plaster layer 39 is applied to the face of boards 21 adjacent the channels 30 and the lugs 38 cooperate with the channel flanges 35 in receiving the plaster from the trowel and facilitating the application of plaster. This form of partition may be constructed as thin as $1\frac{1}{4}$ " and still maintain a thick coating of plaster 39 over the flanges 35, thus avoiding subsequent cracking of the plaster over said flanges 35.

In both types of partitions (Fig. 1), base boards 41 are attached to ground strips 42 and 43 by nails 44. The ground strips 42 and 43 are attached to both sides of the partition, by finishing nails 45 which pass through the plaster board 21, thus securing opposite ground strips together with the partition positioned between said strips. Instead of the clips 27 and 28, the boards 21 may be attached to the studs 17 or 30 by means of clips 47 (Fig. 9) having outstanding fingers 48 for receiving the board edges. A tie plate 49 is pivotally connected to the clip 47 by means of a hinge pin 50, an outstanding flange 51 being formed on the outer end of the plate 49 to be bent about the stud 17 or 30 to hold the clips and boards in position.

The partition is quickly erected at a low cost of labor and materials. The plaster finally applied to both surfaces of the partition serves to bind the various parts together into one monolithic slab of high strength and rigidity.

I would state in conclusion, that while the illustrated example constitutes a practical embodiment of my invention, I do not wish to limit myself precisely to these details, since manifestly the same may be considerably varied without departing from the spirit of the invention as defined in the appended claims.

Having thus described my invention I claim as new and desire to secure by Letters Patent:

1. In a partition structure, a pair of channel strips attached to the floor and ceiling of a room, one flange of each channel being provided with spaced slots, channel studs having webs engaging in said slots, lathing boards secured to said studs,

the upper and lower edges of the partition boards engaging in said channel strips between the unslotted flange of said strip and said studs, and plaster covering both faces of said partition.

5 2. In a partition structure, a pair of channel strips attached to the floor and ceiling of a room, said strips having a web and a pair of outstanding flanges, one flange of each channel being provided with spaced slots, channel studs having webs engaging in said slots, lathing boards supported by said studs, the upper and lower edges of the partition boards engaging in said channel strips between the unslotted flange of said strip and said studs, clips having outstanding fingers engaging abutting edges of said boards, wires connecting said clips to said studs, and plaster covering both faces of said partition.

BRUNO E. BALDUF.
